UNITED STATES PATENT OFFICE

2,372,554

METHOD OF KNITTING HOSIERY AND CIRCULAR KNITTING MACHINE THEREFOR

Bernard Thornton Cole, Burbage, England, assignor to B. Toone (Nottingham) Limited, Nottingham, England

Application July 14, 1942, Serial No. 450,922
In Great Britain March 15, 1941

17 Claims. (Cl. 66—48)

This invention is for improvements in and relating to the manufacture of hose (which expression includes stockings, three-quarter hose and half hose), and like articles knit in the main by rotation and of substantially tubular form but having at least one integral pocket or pouch; the invention also relates to the articles themselves and to a circular knitting machine for their manufacture. Primarily the invention is concerned with the production of the heel and toe pockets in hose and with seamless hose and like knitting machines.

Heretofore in the production of seamless hose on a circular knitting machine it has been the usual practice to knit the leg and foot by rotation but to produce the heel and toe pockets by oscillation. The present invention comprises a method of producing, on a circular knitting machine, a pocket in a rotationally-knitted article wherein initial and terminal courses of knitting are produced on a circular or arcuate series of needles by rotation and between said courses reciprocally-varying groups of needles are caused to retain their loops and to knit (that is to say one group of needles retains its loops and an adjacent group of needles knits and the number of needles in the two groups is varied reciprocally by increasing one group at the expense of the other), said reciprocal variation being effected gradually throughout successive courses of the pocket, whereby suture lines are produced, characterised in that said reciprocal variation and the accompanying knitting of the pocket is effected during rotation. The invention further includes a method of producing by rotation, on a circular knitting machine, a pocket in a substantially tubular and circular-knit article, which comprises knitting at least one course by rotation on the circle or arcuate series of needles, thereafter during rotation excluding the feed thread from a progressively varying (i. e., decreasing and increasing or increasing and decreasing) number of the needles and causing the varying number of needles from which the thread is excluded to hold their loops until they resume knitting activity, whereby suture lines are produced, and finally producing at least one course by rotation on the circle or arcuate lines of needles.

In order to ensure a good suture it is preferred that during the production of the pocket there shall be an overlap, at the suture lines, of at least one needle between the loop-holding and the acting needles. To produce this overlap, during the aforesaid progressive variation

spaced needles at each end of the active group of needles producing the pocket may be changed over from inactivity to loop-holding and vice versa (according to whether narrowing or widening is being effected).

The invention further includes a circular knitting machine, having a needle bed and relatively rotatable needle-operating and thread-feeding means, and needles in the bed, for knitting an article by rotation, characterised by means for producing a pocket, having suture lines, in the article during rotational knitting, said means comprising means for causing reciprocally-varying proportions of the needles to hold their loops and to continue to knit during rotation.

In order that the invention may be better understood reference will now be made to the accompanying drawings in which:

20 Figure 1 shows the foot portion of a stocking, sock, or the like, with heel and toe pouches according to this invention.

Figures 2, 3, 4 and 5 show a portion of a suture line in four alternative forms of pouch;

25 Figure 6 shows in the upper part a development of one of these pouches (e. g., the heel pouch), and below it a development of the knitting cams;

Figure 7 is a continuation of Fig. 6 showing certain cams and pickers, and alongside said cams a view of a needle and a jack.

30 Figures 8 and 9 show the operation of an up-picker which picks up three-quarter butts from the leading end of the active group of heeling needles during narrowing.

35 Figures 10 and 11 show the operation of an up-picker which picks up three-quarter butts from the trailing end of said group.

40 Figures 12, 13 and 14, 15 show the operations on half butts.

45 Figures 16 and 17 are respectively perspective views of the leading and trailing-up-pickers and associated mechanism, and

50 Figures 18 and 19 are respectively perspective views of the trailing and leading down pickers and associated mechanism.

55 Figures 20 and 21 are respectively views of the picking ends of the up-pickers shown in Figs. 16 and 17 and also illustrate the shape of the ends of the down pickers;

Figure 22 shows the end of a trailing picker for the production of the pouch shown in Fig. 4 or Fig. 5.

Figures 23 and 24 are perspective views of

relevant parts of the head of the machine, looking from opposite sides.

Figure 25 is a general view of the machine, showing the control mechanism for the beating yarn fingers;

Figures 26 and 27 are perspective views showing details of the yarn-feeding and cutting mechanism;

Figure 28 is a detail of the cutter.

The article 10 illustrated in Fig. 1 is provided with a heel pouch 11 with suture lines 12, and a toe pouch 13 with suture lines 14. These pockets are of substantially normal appearance but instead of being knitted by reciprocation they are knitted by rotation. To do so, at the commencement of the pocket the instep needles included under the bracket A in Figs. 6 and 7 are moved to a position in which they retain their loops and knitting is continued on the pocket needles B, C, B' while rotation continues. At each of various successive courses in the formation of a pocket as illustrated in Figs. 1, 2, and 6, needles B and B' are progressively moved to the loop-holding position until only the needles C are active. Thereafter the needles B and B' are progressively restored to activity until all the pocket needles are active, after which the instep needles A are restored to activity also. It will therefore be appreciated that this reciprocal variation between two groups of needles, the inactive loop-holding needles and the active pocket-forming needles, results in the production of suture lines such as 12 and 14.

Since the pocket is knitted by rotation the courses of which it consists are not laid to and fro as in ordinary reciprocating knitting, but the fed yarn after being knitted by the last active needle in one course is next knitted by the first active needle at the other end of the group of active needles in the next course. Between the two courses the fed thread is excluded from the inactive needles and it may extend as a float thread from the last needle at the trailing end of the active needles to the first needle at the leading end thereof, such floats being cut away subsequently to the completion of the article or, as is preferred, the thread may be severed at the end of each course of the pouch and the cut end re-introduced at the first needle of the next course. It is preferred to make use of beating feeder; that is to say a thread feeder which is moved into and out of the operative position to feed thread only to those needles which are to knit (e. g., by the employment of mechanism substantially as described in my prior U. S. Patent No. 2,295,450 granted September 8, 1942.

The rotatable needle cylinder 20 is provided with a circular series or full complement of needles 21 having alternate long and short butts 21a, and beneath each needle in the same track there is a jack 22 the butts 22a of which are of contrasting length also. The jacks beneath the instep needles A all have long butts 22a; the jacks beneath the needles B and B' have alternate three-quarter and short butts, while the jacks beneath the needles C have either alternate three-quarter and short butts or all have three-quarter butts. It is these jacks which are employed to effect the progressive reciprocal exchange of needles between loop-holding inactivity and knitting activity. During circular knitting the needle butts 21a follow an active track 23, the needles clear at the clearing cam 27 and the butts descend a guard cam 28 to the stitch cams 29 and 30, being again elevated by cam 31. The lower edge of the cam 28 has a

rebate 28' which is arranged to miss the short needle butts. Thus every second needle is lowered by cam 28 to a slightly greater extent than every intervening needle. This effects a division 5 which permits the feeding eye of the yarn feeder 110 to move between the needles into and out of operative position, the yarn being taken by the needles as their butts descend cam 29. During rotational knitting the butts 22a of all the jacks 10 traverse a low track 26 below the knitting cams just mentioned and below guard cam 34, but the long butt jacks of the instep needles A are engaged by a cam 32 and are raised to a track 25 from which they are lowered to track 26 by bolt cam 33 underneath the clearing cam 27. The three-quarter and short butts of the jacks 15 pass said cam 32 and remain in track 26.

At the commencement of a pocket the bolt cam 33 is withdrawn so that the long butt jacks 20 continue along the track 25 over guard cam 34 which is arranged beneath the knitting cams. This cam has a V-shaped recess 35 immediately below the apex of cam 29. As the needles A descend cam 29 they are lowered on to the jacks 25 22 and the latter are caused to pass down to the apex of the recess 35, but as the jack butts travel up the further slope of the V the needles are raised and their butts are passed up a gap 36 between the cams 29, 30, the said butts being raised by said cam 30 to a loop-retaining idle track 24. Thus all the instep needles are caused to hold their loops, the other needles continuing down cam 30 to knit. The bolt cam 37 is also inserted to a sufficient extent to engage 35 the three-quarter butts of the jacks B, B', and to raise them to a picking level indicated at 38, the short jack butts passing said cam 37. Thus the division is effected between odd and even 40 jacks of needles B, B'. The division is cancelled by cam 41 and the first course of the pouch proper is knitted on needles B, B' after which the division is again made. The three-quarter butt jacks elevated to the picking level 38 (which may be considered to be the odd jacks) are then 45 operated on by up-pickers 39 and 40. The picker 40 picks up the first two three-quarter butts of the group B from level 38 to level 25 as shown in Figs. 8 and 9 and the picker 39 picks the last two-three-quarter butts of group B' from level 38 to level 25 as shown in Figs. 10 and 11, so that the four needle butts associated therewith 50 are caused to pass up the gap 36 and the picked needles hold their loops in the second course. That is to say, the first and third needles at each end of the pouch needles are selected to hold their loops. The cam 37 is now pushed right in to raise all the jack butts of active needles 55 to picking height 38, said butts being lowered by cam 41. After the third course has been 60 knitted in this manner the pickers 39, 40 are again rendered operative to pick the first two short butts (Figs. 12 and 13) and the last two short butts (Figs. 14 and 15). That is to say, the butts associated with the second and fourth 65 needles from each end of the group of heeling needles then active are picked. Cam 37 is now withdrawn to miss the short butts and the fourth course is knitted on the remaining active pouch needles. This sequence of picking is continued 70 until all the needles B and B' have been moved to the loop-holding track.

The sequence of picking is therefore needles 1 and 3; 2 and 4; 5 and 7; 6 and 8 and so on, the odd numbered needles being those whereof the jacks 22 have three-quarter butts and the

even needles those whereof the jacks have half butts. As a result at certain courses during the narrowing of the pouch there is an overlap of at least one needle between the inactive loop-holding needles and the active pouch knitting needles. For example during the knitting of the second course of the series the third needle is inactive and the second and fourth needles are active with the result that a series of thread loops are accumulated as knobs on the third needle (such loops being actually accumulated on the third, seventh and eleventh, etc., needles). This is shown in Fig. 2, wherein the needle wales and courses are numbered consecutively.

The thread feeder such as 110a (Fig. 25) moves into operation as the first of the active pouch-knitting needles approaches the knitting cams and out of operation as the last of said active needles leaves the knitting cams, and the float thread at each course is either cut subsequently or the withdrawn thread is cut immediately whereby loose ends are produced at the suture lines, as will be seen in wales 1 and 2, 5 and 6, etc., of Fig. 2. In this figure the cut ends are for the sake of clarity shown very short. In practice they are somewhat longer and may either be knitted by or caught up into knobs formed in the third, seventh, etc., wales.

After all the needles B, B' have been moved to the loop-holding position it is necessary to re-introduce them progressively into activity. They are re-introduced in the same sequence by down pickers 42, 43; that is to say the picking sequence is 1 and 3, 2 and 4, etc., at the leading end of group B' and at the trailing end of group B. At least one course is knitted on the remaining active needles C, the cam 37 being withdrawn to miss the three-quarter butts. Dividing cams 44 and 45 are pushed part-way in and remain for two courses. The cam 44 raises the long and three-quarter butts from track 25; the long butts are immediately returned by cam 45 but the three-quarter butts continue until lowered by cam 27 and by the action of the needles descending cams 28 and 29. The short butts miss the cam 44 and continue at the down-picking level in track 25. In the second of these two courses the down-pickers 42, 43 are rendered operative to pick the last two short butts associated with needles B and the first two short butts associated with needles B' down to the track 26. As a result the associated needles descend the cam 30 and are re-introduced into knitting activity. For the third and fourth courses of the series of four courses cams 44, 45 are retracted to miss the three-quarter jack butts so that the three-quarter and half butts continue at the picking level 25. In the third course the down pickers 42, 43 are inactive; but they are rendered active after the fourth course has been knitted to pick down respectively the last two three-quarter butts of the jacks of group B and the first two three-quarter butts of the jacks of group B'. This four-course sequence continues until all pouch needles are re-introduced into knitting activity when the widening pickers 42, 43 are rendered inactive and the cam 33 is re-introduced to lower the long butt jacks so that the instep needles of group A are again rendered active and tubular knitting proceeds.

It will of course be understood that during this widening of the heel the thread is introduced and withdrawn in the same manner as during the narrowing.

In a modification illustrated in Figure 3 at

spaced courses throughout the narrowing and widening of the pouch all the inactive needles are caused to knit, for example by retracting that part of cam 34 that is indicated at 34'.

Reference will now be made to the construction of the leading end pickers 40 and 43 and the trailing end pickers 39 and 42 (Figs. 16-21). Figure 20 is an enlarged view of the picking end of picker 40. It will be seen that it is provided with a ledge 40a of sufficient length to receive two of the jack butts 22a and, being driven by the first of said butts, operates in the well-known manner. Down picker 43 is of substantially similar construction as may be seen from Fig. 19, and Fig. 20 may be considered to be an inverted view thereof. Fig. 21 is an enlarged view of the picking end of the trailing up-picker 39. It will be seen that this picker is provided with a ledge 39a of sufficient width to receive one of the jack butts, a driving projection 39b adapted to enter between two consecutive butts at the picking level (which, owing to the division illustrated in Fig. 10, is equivalent to that between two odd or even butts), a recess 39c to accommodate the trailing end butt, and a platform 39e for riding on the underside of the line of butts passing said picker. The operation of the picker is as follows: When the picker is rendered operative the platform 39e rises against the underside of the butts which pass along over it and prevent the picker operating until the last two butts, travelling from right to left, arrive at the position in which they are shown in Fig. 10. The projection 39b thereupon enters between said butts and these butts drive the picker to make its picking movement. The end of the down picker 42 is of substantially similar inverted construction as may be seen from Fig. 18.

A further modified heel pocket is illustrated in Fig. 4. Here the picking sequence is 2, 1, 4, 3, 6, 5, etc. For this purpose the leading end pickers are similar to those shown in Figs. 16, 18 and 20 except that the ledge is of sufficient width to accommodate one butt only. The end of a trailing end picker 39 is illustrated by way of example in Fig. 22. It will be seen that the ledge 39a is omitted but the driving projection 39b, the butt recess 39c, and the platform 39e are retained. This figure may be taken as showing an inverted view of a trailing down-picker, and further details of said trailing up-pickers and down-pickers are as shown in Figs. 17 and 19. In Fig. 4 there is a difference between the wales 3 and 7 and the wale 11 because at spaced revolutions the machine needles are caused to knit.

A still further modified form of pouch is shown in Fig. 5. Here the picking sequence is 3 and 4, 1 and 2, 7 and 8, 5 and 6, etc., and for this purpose instead of the three-quarter and half butts of the jacks 22 associated with the needles B and B' being alternated 1 and 1 they are alternated 2 and 2 in the needle cylinder.

It will be seen that a characteristic of the fabrics shown in Figs. 2-5 is that in certain courses, both during narrowing and widening, there is an overlap between the active and the loop-holding needles.

The up-pickers 39 and 40 are shown in their inoperative position in Fig. 7. They are controlled from the drum 113 by lever 44, link 45 and bell-crank-lever 46 which slides a ring 47 against the action of a spring 48 (Fig. 23). This ring is connected by link 49 to a lever 50 pivoted to the platform 51 at 52. Movement of the ring

47 to the left Fig. 23, rocks the lever 50 and causes the leading picker 40 to swing up guide cam 53 to the inoperative position, the said picker being pivoted at 54 to a block 55 which is itself pivoted to the platform at 56. When the ring 47 is moved to the right the spring 57 pulls the picker down the cam 53 to its operative position resting on guide cam 58, where it is ready to pick the first two butts meeting it. The trailing picker 39 is likewise pivoted at 59 to a block 60 pivoted to the platform 51 at 61. Its outer end is connected by spring 62 to an E-shaped lever 63 which is pivoted at 64 to a bracket 65 on the platform 51 and which is drawn downwards by a tension spring 66. The said lever 63 thus holds the picking end of the picker 39 in the operative position in which when the projection 39b engages between the butts the said picker is free to swing up the guide cam 67. When the ring 47 is moved to the right, Fig. 23, a wedge 68 thereon is inserted beneath the lower end 63a of one arm of the E-shaped lever 63 and the latter is raised as shown in Fig. 17 so that the spring 62 causes the picking end of picker 39 to be lowered to its inoperative position.

The down pickers 42, 43 are controlled by a similar ring 47', drawn towards the left in Fig. 24 and the right in Figs. 18 and 19 by spring 69, and controlled from the drum 113 by lever 101 and link 102. Trailing down-picker 42 is pivoted at 70 to block 71 which is pivoted at 72 to the platform 51, and the outer end of the picker is connected by tension spring 73 to a lever 74 pivoted at 75 to a lug 76 on said platform. Movement of the ring 47' to the right in Fig. 18 brings a headed pin 77 carried by the ring over a V-shaped recess 74a in lever 74 so that the latter is free to rise under the influence of a compression spring 78 whereby the picking end of the picker 42 is lowered to picking position. Thus when the picker engages a butt it swings on its pivots 70, 72 and travels obliquely downwards along the face of guide cam 79. The leading down-picker 43 is likewise pivoted at 80 to a block 81 pivoted to the platform 51 at 82. Its outer end is connected by a tension spring 83 to a lever 84 pivoted at 85 to lug 86 on the platform 51. Movement of the ring 47' to the right (Fig. 19) carries a headed pin 87 on the ring into engagement with an inclined face 84a on the lever 84 and lowers the said lever against the action of compression spring 88 so that by the action of the spring 83 the picking end of the picker 43 is pulled upwards to its operative position underneath a guard cam 90. In that position the picker is free to pick obliquely down the face of guide cam 89.

The cam 33 is arranged to be pushed inwards by a bell-crank-lever 91 and push rod 92, Fig. 24, operated from the drum 113. The dividing cam 37 is pushed inwards by lever 93, Fig. 23, bars 94 and 95 operated by lever 96 from said drum 113. A pin 97 protrudes from the bar 95 through a slot 98 in bar 94 and is connected to said bar 94 by spring 99. When the lever 96 is moved by the first half of a stepped cam on drum 113 the spring 99 is sufficiently strong to carry bar 95 with it and to rock lever 93 to push in the cam 37. Further movement of the bar 94 on the second half of the stepped cam introduces cams 44 and 45 by means of a lever 100 (Fig. 24).

The mechanism, Fig. 25, by which the feeders 110 are controlled from the drum 113 is substantially similar to that employed on Scott & Williams machines for splicing, and consists of a hori-

zontally guided bar 140 extending fore-and-aft of the machine, and adjustable lengthwise by a cam 141 at the rear, this cam being stepped round at appropriate intervals by mechanism well understood in the art. The shape of this cam 141 is such as to determine the shapes of the spliced areas 8 and 9 (Fig. 1) and also the dwell of the appropriate feeder in the feeding position during the production of the pockets 11 and 13. On the bar 140 a substantially horizontal lever 142 is pivoted intermediate its ends, which lever 142 when rocked on its pivot (as it is on each revolution on the main shaft 144) serves by means of a cross lever 124 to raise the push rod 111x (Fig. 26) to withdraw the pouch feeder 110a or the splicing feeder 110b. In order to rock this lever 142 there is an operating cam 143 on the main shaft 144 which operates a substantially vertical rock arm 145. This rock arm 145 carries a lift plate 146 which engages a nose 147 on the front end of lever 142. Obviously according to the endwise adjustment of the slide bar 140, as determined by cam 141, the rock lever 142 is thus engaged and raised earlier or later 25 in the forward stroke of the rock arm 145. It will therefore be obvious that the time that the selected feeder dwells in the feeding position in each revolution is controlled. It may be mentioned that the initial introduction of the selected 30 feeder and its final removal from operation is governed by cams 148 operating through push rods such as 111a and 111b. (Fig. 26.)

The lift plate 146 is provided with two levels, one of which effects the first portion of the lift 35 of the operative feeder towards the inoperative position, and the second portion of which effects the closure of a cutter 129, 130 to cut the withdrawn thread. It will be seen from Fig. 26 that each of the push rods 111a and 111b is stepped 40 and a pin 200 projects from rod 111x across said step. Thus whichever of these rods 111a or 111b is raised by a cam 112 to raise a feeder to inoperative position the rod 111x is raised also (to operate the cutter), and when the rod 111x is raised in each revolution a pin 200 serves to raise that 45 feeder which is operative.

The cutting mechanism is substantially similar to that described in my above mentioned prior U. S. Patent No. 2,295,450, but somewhat modified to adapt it better to the functions that it now has to perform. Pivoted to the latch guard ring 121 at 125 there is a knife arm 126 carrying a knife block 127 which is equipped with a stationary knife 128 and a movable knife 130, the latter being movable by plunger 131 engaged by a lever 161 pivoted to the knife arm 126 at 162. The outer end of said lever 161 overlies an adjustable tappet 128 in an arm 116 which arm is pivoted to the feeder bracket 115 at 114; the said tappet 128 normally rests on the latch ring 121 and determines the rest position of the arm 116. The latter is also provided with an adjustable tappet 117 overlying the end of push rod 111x, the arrangement being such that when the push rod 111x is raised the operative feeder is raised towards the non-feeding position by pin 200, the arm 116 is raised shortly afterwards, and finally the cutter 129, 130 is operated to cut the withdrawn thread. The arm 116 likewise has two feeder eyes 122a 122b and tension devices 119a and 119b (each consisting of a pair of cymbals) the yarn running through the appropriate eye 122a or 122b, device 119a or 119b to the eye of the feeder 110a or 110b. As either feeder is lowered

to operative position the arm 116 descends also and is finally brought to rest before the feeder. The continued movement of the feeder results in the loose end of yarn gripped by the cymbal device 119 being drawn back through the feeder eye.

Fig. 25 shows the knife arm 126 raised to an operative position, the push rod 149 resting on cam 148, when the operation of the cutter in each course is unnecessary.

It will be obvious that irrespective of which feeder 100a, 100b is employed, that feeder is withdrawn and the cutter 129, 130 is operated when the push rod 111x is raised. Since the two feeders feed their yarns at different angles, it is advisable to provide means for ensuring that each yarn is taken correctly by the cutter. This is best achieved by shaping the cutter blade 129 as shown in dotted lines in Fig. 28.

It is further advisable to provide means for locating the cut end of yarn at the inside of the needle circle, so that when the withdrawn feeder is re-introduced the yarn will be introduced with certainty to the correct needle. This means is shown in Fig. 27 as consisting of two members 103, 104 between which the yarn is carried as the feeder rises and as the rotation of the cylinder carries the yarn into the knives 129, 130.

In a modification, all the needles other than a group at the back of the leg (e. g., needles C) are moved to loop-holding position, widening is effected by gradually introducing into activity needles from the ends of the inactive group, narrowing is effected by gradually moving needles at the ends of the active group to loop-holding position (e. g., until all the needles other than the first group are inactive), and all the inactive needles are then re-introduced into activity, these changes being effected during rotation. This produces a pocket with the suture lines disposed substantially in the form of a diamond.

During the leg and foot, the jack butts may be permitted to remain at level 26 throughout each complete revolution, by withdrawing cams 32 and 37.

I claim:

1. A method of producing by rotation, on a circular knitting machine, a pocket in a substantially tubular and circular-knit article, which comprises knitting at least one course by rotation on the arcuate series of needles, thereafter during rotation excluding the fed thread from a progressively varying (i. e., decreasing and increasing or increasing and decreasing) number of the needles and causing the varying number of needles from which the thread is excluded to hold their loops until they resume knitting activity, whereby suture lines are produced, manipulating the needles to produce a locked loop formation along the suture lines, and finally producing at least one course by rotation on the circle or arcuate series of needles.

2. A method according to claim 1, wherein, during the production of the pocket, there is an overlap at the suture lines of at least one needle between the loop-holding and the active needles.

3. A method according to claim 1, wherein, during the aforesaid gradual variation, spaced needles at each end of the active group of needles are changed over, in the order first and third, second and fourth, fifth and seventh, and so on, from activity to loop holding and vice versa according to whether narrowing or widening is being effected.

4. A method according to claim 1, including the steps of cutting the fed thread at the end of each course of the pocket and introducing the cut end to the needles at the beginning of the next course.

5. A circular knitting machine, having a needle bed and relatively rotatable needle-operating and thread-feeding means, and needles in the bed, for knitting an article by rotation, characterised by means for producing a pocket, having suture lines, in the article during rotational knitting, said means comprising means for causing reciprocally-varying proportions of the needles to hold their loops and to continue to knit during rotation, and means for producing a locked loop structure along the suture lines.

6. A circular knitting machine, having a circular needle bed and relatively-rotatable needle-operating and thread-feeding means for knitting an article by rotation, characterised by the combination of a knitting track for rotary knitting and a loop-holding track, mechanism for diverting a group of needles at the commencement of a pouch from the knitting track to the loop-holding track, leaving a group of needles in the knitting track, mechanism for changing the needles at the ends of these groups between the two tracks, first in one direction and then in the other, while rotary knitting continues in the production of a pouch with suture lines and for producing a locked loop structure along said suture lines, and mechanism for returning the first said group of needles from the loop-holding track to the knitting track at the termination of the pouch.

7. A machine according to claim 5, having change-over mechanism for effecting a progressive reciprocal variation between groups of loop-holding and active needles by changing over end needles of the groups from one function to the other, which mechanism operates in alternating courses on a needle spaced inwards from the end of one of the groups and on the end needle, for the time being, of said group, whereby the ends of the two groups are caused to overlap as they are reciprocally varied.

8. A machine according to claim 6, having change-over mechanism, operable during rotation at both ends of one of the aforesaid groups of needles, for effecting a progressive reciprocal variation between groups of loop-holding and active needles by changing over end needles of said groups from one function to the other, which mechanism comprises means for changing over, in alternating courses, the end needles of said one group and a needle spaced inward from each end of said group, and for thereby causing the ends of the two groups to overlap as they are reciprocally varied.

9. A machine according to claim 5, comprising a feeder for feeding a thread to the needles in the production of the pocket, a cutter for cutting the fed thread extending from the last needle, for the time being, of the active group, and means for operating said cutter.

10. A machine according to claim 5, incorporating butts associated with the needles and picker mechanism for operating at the leading and trailing ends of a group of needles in narrowing and widening the pocket, which mechanism comprises a trailing-end picker having a driving member for engagement in front of a butt to be picked, and a positioning surface for engaging with the butts as relative movement occurs between them and the picker and for thereby preventing en-

gagement of the driving member until said relative movement terminates the engagement between the butts and positioning surface.

11. In a circular knitting machine of the kind having a needle bed, relatively-rotatable needle-operating and thread-feeding means, needles in the bed, and butts or their equivalent associated with the needles; mechanism for producing a pocket with suture lines in the article during rotary knitting by dividing the needles into an active group and an inactive group and by effecting the reciprocal exchange of needles between the ends of the groups in narrowing and widening the pocket, which mechanism includes dividing means for operating in spaced courses to divide alternate butts of a group of needles between a picking level and a non-picking level, means for directing all said butts into the picking level in intervening courses, and a picker for picking the end butt from the picking level in said spaced and intervening courses whereby a butt inwards from the end of the said group is picked in said spaced courses and the end butt is picked in said intervening courses.

12. A machine according to claim 5, having a divided stitch cam affording a butt passage between its two parts, and means for passing the butts of the loop-holding needles through said passage in the production of the pocket, the other needles completing the descent of the cam to knit.

13. A machine according to claim 5, having butts on the needles, jacks beneath the needles, butts on the jacks, a divided stitch cam affording a butt passage through it, two tracks for the jack butts, one for the jack butts of active needles and the other for the jack butts of loop-holding needles, means for changing over the jack butts from one track to the other, and a jack raising cam in the second-mentioned jack butt track for elevating the jacks and associated needles and for thereby diverting the butts of said needles through the butt passage.

14. In a circular knitting machine having a needle bed and relatively-rotatable needle operating means and thread feeding means, and needles in the bed, for knitting an article by rotation; mechanism for producing a pocket having suture lines in the article during rotational knitting, said mechanism comprising means for causing reciprocally-varying proportions of the needles to hold their loops and to continue to knit during rotation and for pro-

ducing an overlap between the active and inactive needles, and a beating feeder for feeding thread to the active needles and for excluding it from the loop-holding needles.

15. In a machine according to claim 6, a feeder for feeding a thread to the active needles in the production of the pocket, a cutter for cutting at each rotation the fed thread extending from the last needle, for the time being, of the active group, means for operating said cutter at each rotation during the production of the pocket, and means for introducing the cut end of thread to the first needle, for the time being, of the active group at the next rotation.

16. A seamless hose or half hose machine for knitting an article of footwear by rotation and having a needle bed and relatively-rotatable needle-operating cams and thread feeder, and needles in the bed; characterized by mechanism for knitting a pouch having suture lines in said article during rotation, which mechanism comprises means for dividing the needles into active and inactive groups by moving needles to a loop-holding position, means for effecting an exchange of the end needles between the two groups in effecting a reciprocal variation thereof to shape the pocket and to produce suture lines, means for restricting the fed thread to the active needles, means for producing loop accumulations along the suture lines, and means for restoring inactive needles en masse to activity at the termination of the pocket.

17. A circular knitting machine, having a needle bed and relatively rotatable needle-operating means for knitting an article by rotation, needles in the bed, and mechanism for knitting a pocket having suture lines in the article during rotation, said mechanism including means for causing reciprocally-varying proportions of the needles to hold their loops and to continue to knit during rotation, a feeder for introducing a yarn in each rotation to the needles that continue to knit and for withdrawing it so that it is excluded from the loop-holding needles, means for severing the withdrawn yarn at each rotation, and means for reducing, subsequent to severance, the length of yarn extending from the feeder to the severed end for presentation of the reduced yarn end to the said knitting needles at the next rotation.

BERNARD THORNTON COLE.
